UNITED STATES PATENT OFFICE.

CHARLES DESHNER, OF MAYBURG, PENNSYLVANIA.

CAR-REPLACING DEVICE.

1,164,580.

Specification of Letters Patent. Patented Dec. 14, 1915.

Application filed May 8, 1915. Serial No. 26,824.

To all whom it may concern:

Be it known that I, CHARLES DESHNER, a citizen of the United States, residing at Mayburg, in the county of Forest and State of Pennsylvania, have invented new and useful Improvements in Car-Replacing Devices, of which the following is a specification.

This invention relates to car replacing devices, and it has for its object to produce a replacing device composed of right and left hand members which when placed adjacent to the rails of the car track in advance of derailed wheels will operate to lift the latter and replace them on the rails.

A further object of the invention is to produce a simple and efficient device of the character described which is equipped with anti-friction members in the nature of rollers which will materially reduce friction as the wheels are being replaced on the rails.

A further object of the invention is to produce a simple and effective car replacing device of improved construction which will be light in weight so that it may be conveniently carried and arranged in position for use or for transportation.

With these and other ends in view which will readily appear as the nature of the invention is better understood, the same consists in the improved construction and novel arrangement and combination of parts which will be hereinafter fully described and particularly pointed out in the claims.

In the accompanying drawings has been illustrated a simple and preferred form of the invention, it being, however, understood that no limitation is necessarily made to the precise structural details therein exhibited, but that changes, alterations and modifications within the scope of the claims may be resorted to when desired.

In the drawings, Figure 1 is a plan view of a portion of a car track showing the right and left hand members of the replacing device arranged in position for operation. Fig. 2 is a similar view showing the position of the wheels when they have climbed the replacing devices and are almost ready to be replaced on the rails. Fig. 3 is a transverse sectional view taken on the line 3—3 in Fig. 1. Fig. 4 is a transverse sectional view taken on the line 4—4 in Fig. 2. Fig. 5 is a bottom plan view of one of the replacing members. Fig. 6 is a view in side elevation of one of the replacing members. Fig. 7 is a

longitudinal sectional view taken on the line 7—7 in Fig. 1.

Corresponding parts in the several figures are denoted by like characters of reference.

The improved device comprises two replacing members A and B which for purposes of description will be known respectively as the right and left hand members. The two members are of identical construction, except that, as will be understood, they are made "right" and "left".

Each of the members A and B consists of a body, the top face of which constitutes an inclined plane, being inclined from the rear end in a downward and forward direction. The said top faces, which are designated by 15 and 16, are also inclined laterally in opposite directions, each being provided at its high side with a longitudinal rib, said ribs being designated by 17, 18, and 70 said ribs being relatively wide at their high ends and relatively narrow at their low ends.

The members A, B are made hollow on their undersides for the sake of lightness and are provided with reinforcing webs 19 for the 80 sake of strength. The top portion of each member is provided at its high end with a slot 20, the side walls of which are provided with bearings for a plurality of obliquely disposed rollers 21 which are set closely together and are made of ample strength to resist any strain to which they may be subjected.

The top portion of each rib 17, 18 is provided at its high end with a longitudinal slot 22 serving to support anti-friction 90 rollers 23 which project but slightly above the faces of the respective ribs. Each member A, B is provided with downwardly extending spurs or prongs 24 adapted to engage the ties of the track so as to prevent 95 lateral displacement of the respective members under the stress to which they will be subjected when in use.

In the operation of this invention, the members A and B are placed on the track 100 in advance of the car wheels which have been derailed, as indicated in Fig. 1 of the drawings. When the car is moved forward, the flange of one wheel will ride on the top face of one member, while the tread of the 105 other wheel will ride on the rib extending upwardly from the top face of the other member. As shown in the drawing, the member A is located between the rails, while the member B is located outside the prox- 110

mate rail, but this condition may be reversed according to the conditions of the derailment. As the wheel traveling on the member A rides up the inclined plane forming the top face of said member, the tendency will be for the said wheel to slide down the lateral incline, but this tendency will be counteracted by the flange of the wheel riding on the rib 18 of the member B which 10 will be drawn against the side of the head of the proximate rail. When the top of the respective members has been reached by the wheels, the flange of the wheel riding on the rib 18 of the member B will have reached 15 the top of the rail head and will be free to pass over the same. This condition is brought about by the wheel traveling on the member A which will now gravitate in the direction of the proximate rail placing the 20 tread of the wheel on the rail head, and in so doing the wheel traveling on the member B will be carried across the head of the proximate rail until its flange drops to the proper position adjacent to the inner side of 25 the rail head. The wheels will thus be replaced on the rails in a simple, rapid and effective manner.

It has been stated in the foregoing that the rollers 21 are obliquely disposed. This 30 arrangement of said rollers will not interfere with the movement of the wheel flange engaging the same in the direction of the head of the proximate rail, but owing to the oblique arrangement the movement of the 35 wheel will be somewhat retarded, thereby avoiding all danger of the wheel passing

over the replacing device without being seated on the rail.

Having thus described the invention what is claimed as new, is:—

1. A car replacing device comprising right and left hand members, each having a top face forming a longitudinally inclined plane, said planes of the two members being also laterally inclined in opposite directions, and 45 said members being provided with longitudinal ribs at the edges of the lateral inclines.

2. In a device of the class described, a member having a top face constituting a longitudinally inclined plane, said top face 50 being also laterally inclined and provided with a longitudinal rib along its high edge, said top face being provided at its high end with a plurality of obliquely disposed anti-friction rollers.

3. A device of the class described comprising right and left hand members, each having a top face forming a longitudinally inclined plane, said top face being also laterally inclined and provided at its high end 55 with a plurality of obliquely disposed anti-friction rollers, said member being provided along the high edge of its top face with an upstanding rib, said rib having at its high end a longitudinally disposed anti-friction 60 roller.

In testimony whereof I affix my signature in presence of two witnesses.

CHARLES DESHNER.
